Fig. 3

FIG. 1 is a perspective view of a cabinet showing my new design.

FIG. 2 is an enlarged fragmentary perspective view showing the upper edge of one of the doors and the immediately adjacent cabinet portions in greater detail, as seen substantially on the line 2—2 of FIG. 1.

FIG. 3 is a fragmentary plan view of one edge of one of the doors to show a detail of such edge.

The essential feature of my design resides in the combination of the particular door members together with the metal-sheathed projecting moldings extending parallel to the vertical side edges of each door and protruding beyond the front surface of the same, each projecting molding having an outwardly flared inner surface and said flared surface contrasting in appearance with the material of the front surface of said doors, substantially as shown.

The dotted line showing of the door and drawer pulls is for illustrative purposes only.

The side of the cabinet not shown is similar to the side which is shown and the back of the cabinet is plain.

I claim:

The ornamental design for a cabinet, substantially as shown and described.
